United States Patent Office.

JONATHAN QUIPP AND ROBERT LAW, OF BUFFALO, NEW YORK.

Letters Patent No. 93,745, dated August 17, 1869.

IMPROVEMENT IN STEAM-GENERATORS.

The Schedule referred to in these Letters Patent and making part of the same.

To all whom it may concern:

Be it known that we, JONATHAN QUIPP and ROBERT LAW, of Buffalo, in the county of Erie, and State of New York, have invented a new and useful Improvement in Steam-Generators; and we do hereby declare that the following is a full, clear, and exact description thereof, which will enable others skilled in the art to make and use the same, reference being had to the accompanying drawings, forming part of this specification, in which—

Figure 1 represents a front end view, partly broken out.

Figure 2 represents a side view, also partly broken.

Similar letters of reference indicate corresponding parts.

We use two or more boilers. The one, A, placed over the fire-box, we call the primary boiler, and it is an ordinary flue-boiler; the two upper boilers, C D, we call the secondary boilers, to distinguish them.

There are also flue-boilers with double ends, as shown, where part of the outside end is left off on the left hand, in both figures.

The flues in the secondary boilers run through from one inside end to the other, and the outer end or flap covers the entire end of the boiler, leaving a space between it and the flues, thus leaving the flues and spaces at the ends a free communication.

We generate steam in the primary boiler to the desired pressure, then open the cock in the pipe E, connecting the three boilers, when the steam rushes into the secondary boilers, filling the flues and end spaces with steam at a high pressure.

The flues in the secondary boiler or boilers are much smaller, and put very close together, so as to cut up the water contained in them as much as possible.

When the steam is first let on the cold boilers, it condenses very rapidly, but after steam is up, it condenses very slowly.

The pipes connecting the boilers are placed so that the condensed steam can return again to the primary boiler, through the same pipe that admits the steam. As the condensed steam returns again to the primary, there can be but little loss of water in that boiler; still there will be some, and to replenish, we open the cock in the pipe F, on the right, connecting the pri-

mary, A, with one of the secondary boilers. This pipe goes through both heads to the water.

The secondary boilers are supplied with pumps in the usual way.

After the steam is up, the small amount of fuel required to keep it up, exhibits an immense economy over the present mode of generating steam, as we have demonstrated by experiment.

There is no steam drawn away from the first boiler, nor any cold water thrown in, so we only have to keep up the steam in that boiler. But the greatest point gained, is the tremendous ebullition that is obtained in every part of the boilers.

When a fire is built under an ordinary boiler, it is intensely hot just over the fire, but as the boiler extends beyond the fire, it gradually grows cooler, until finally, one can bear a hand on it. There is a fearful loss somewhere. By this method, the steam or heat is forced into every interstice, and held there, thus getting and using the greatest possible heating-surface.

Another point is, using so little water in the primary boiler, there can be but little deposit or sediment.

Then, again, the flues in the secondary boilers, using nothing but steam, must always be very clean, and they are very safe from explosions, as the water in the primary boiler cannot very well get below the flues, and the flues in the secondary boilers cannot be made hot enough to be dangerous.

Having thus described our invention,

What we claim as new, and desire to secure by Letters Patent, is—

1. The improved mode herein described, of generating steam by a system of primary and secondary boilers, arranged to concentrate the heat of the fire upon the primary boilers, and to discharge the steam generated therein into the heating-space of the secondary boilers, for generating steam therein for use, substantially as specified.

2. The arrangement of the pipes E and F, with relation to the primary and secondary boilers, as herein shown and described.

JONATHAN QUIPP.
ROBERT LAW.
